UNITED STATES PATENT OFFICE

98,181

DESIGN FOR AN ELECTRIC FLATIRON

Raymond E. Patten, Bridgeport, Conn., assignor
to General Electric Company, a corporation of
New York

Application October 22, 1935, Serial No. 59,162

Term of patent 14 years

To all whom it may concern:

Be it known that I, Raymond E. Patten, a citizen of the United States, residing at Bridgeport, in the county of Fairfield, State of Connecticut, have invented a new, original, and ornamental Design for an Electric Flatiron, of which the following is a specification, reference being had to the accompanying drawing, forming a part thereof.

The accompanying drawing shows in Fig. 1 a

perspective view of an electric flatiron embodying my new design, and in Fig. 2 an elevation on a smaller scale illustrating the side of the flatiron opposite to that shown in Fig. 1.

I claim:

The ornamental design for an electric flatiron substantially as shown, and described.

In witness whereof, I have hereunto set my hand.

RAYMOND E. PATTEN.
